UNITED STATES PATENT OFFICE.

LEWIS F. BETTS, OF NEW YORK, N. Y., ASSIGNOR OF ONE-HALF TO ROBERT E. DIETZ, OF SAME PLACE.

LANTERN.

SPECIFICATION forming part of Letters Patent No. 355,297, dated January 4, 1887.

Application filed July 2, 1886. Serial No. 206,902. (No model.)

To all whom it may concern:

Be it known that I, LEWIS F. BETTS, of New York city, county of New York, and State of New York, have invented certain new and useful Improvements in Lanterns, of which the following is a full, clear, and exact description, reference being had to the accompanying drawings, and to the letters of reference marked thereon.

10 My invention has relation to that class of lanterns or analogous illuminating apparatus wherein the products of combustion are discharged near or in the region of the point or points at which fresh air for the support of combustion is introduced, the inlet for air and outlet for products of combustion being in close proximity to secure certain balancing effects during movement of the device, or when subjected to wind-currents, as is now 20 well understood.

Among the objects of my invention are the production of a simple, compact, and efficient lantern or lamp having a closed reflector within the exterior casing, and a passage for currents from the exterior to the under side of the burner-cone, provision for balancing or counterbalancing the currents inside and outside the reflector, and to secure other advantages, as will hereinafter appear.

30 To accomplish all of this my improvements involve certain new and useful peculiarities of construction and relative arrangements or combinations of parts, all of which will be herein first fully described, and then pointed out in the claims.

35 In the accompanying drawings, forming part of this specification, Figure 1 is a front elevation, and Fig. 2 a side elevation, of a hand-lantern constructed and arranged for operation in accordance with my invention and involving my improvements. Fig. 3 is a side elevation, and Fig. 4 a top or plan view, of the reflector detached from the exterior casing.

40 Fig. 5 is a vertical axial section. Fig. 6 is a cross-section through line $x-x$ of Fig. 5. Fig. 45 7 is a view in side elevation, showing the upper part of the structure turned down to expose the burner for lighting.

In all these figures like letters of reference, 50 wherever they occur, indicate corresponding parts.

Though the device shown is in the form of a hand-lantern, it will readily appear that the bail is not necessary, and that the device in its improved form may be used after the manner 55 of any lamp or illuminating contrivance.

A is the oil-fount, of which the bottom piece, *a*, is curved upwardly, to prevent contact, except at the edges, with any object upon which the fount may rest. The burner is connected 60 with the top of the fount by a simple joint, so that it may be readily removed from its seat, and the cone *B* of the burner is perforated at bottom, so as to admit air for the support of combustion.

65 C is the exterior casing of the lantern, which in the example shown is six-sided, but which may be made with any number of sides, or variously curved, as may be desired.

D is the reflector, secured within the casing 70 by a flange in front and a removable screw, as *d*, in the rear, the screw passing through the casing and entering a nut, as *b*, upon the reflector. Between the reflector and the walls of the casing is an enlarged space for the passage 75 of fresh air—that is, it is enlarged beyond the capacity of any exposed tubes, such as are ordinarily employed to conduct air-currents in lamps and lanterns. The lower portion of the reflector is perforated in such 80 manner as to receive the burner-cone, fitting it in a practically tight or close joint all around, and the upper portion is provided with a short section of tube or pipe, *D'*, locked in place, as by the flanges *d' d'*, and arranged 85 to fit the lower mouth of the smoke-conduit *E*. The casing is hinged, as at *c*, upon an upwardly-extending rim, *F*, secured upon the oil-fount. This rim is inclined downwardly toward the fount, and receives the lower portion 90 of the casing when the latter is locked in place, guiding it properly toward its seat and protecting it from damage or accidental disarrangement.

To expose the burner-cone for trimming the 95 wick or for lighting the burner, the casing is simply to be tipped back, as in Fig. 7. A spring-catch, *e*, engages with a wire loop, *f*, secured upon the casing, and locks the casing in closed position. The loop *f* extends down 100 beyond the casing far enough to afford convenient access to spring *e*, and up along one side

far enough to afford substantial abutment for the hinged door to strike against when closed. The ratchet-shaft g projects out to one side, and enters a notch, h , in the casing when the latter is closed to final position.

When the casing is swung back upon its hinge, the reflector clears the cone B without disturbing it. The cone is of necessity longer than the ordinary forms, so that the flame will be produced at or in the focus of the reflector; and in order that the casing and reflector may be tipped back upon the hinge the hinge is considerably elevated above the oil-fount, as upon the highest part of the inclined rim, as shown.

The smoke-tube E has a cap, E' , projecting slightly beyond the vertical walls of the tube, and below the opening between the cap and tube (through which the products of combustion pass) is a narrow projecting flange, E'' , the arrangement being such as to form an efficient ejector at the discharge opening or outlet for products of combustion, so that no matter in what direction the lamp or lantern be moved, or from what direction air-currents may strike it, the effect will be to exhaust the contents of the tube E and never to reverse the current in the tube.

Upon the casing C is an upwardly-extending tube, F' , of slightly larger diameter than E , within which E is secured, and within or through which currents of fresh air flow to the space between the casing and reflector, and thence to the under side of the burner-cone. The upper mouth of this tube is supplied with an injector, G , one part of which depends within the tube and the other part outside of it, the inner portion being slightly removed from the tube E . Upon the sides of F' are openings, as $i i$, formed by cutting the material of the tube and bending the flaps $i' i'$ inwardly, substantially as shown. Whenever the lamp is suddenly elevated, air is injected between G and E . When it is suddenly lowered, the overhanging portion of G directs the currents into F' , accomplishing like injecting effects. When it is moved or swung in any direction other than vertical, air enters at the openings i and is turned downwardly by the flaps i' , and whatever currents or movements produce injection of fresh air produce also at the same time exhaustion of products of combustion from the smoke-tube, so that, however the device may be moved or exposed, the current of air through the burner-cone is always in one direction, (upward,) and thus smoking of the flame or extinguishment thereof entirely obviated.

The flange E'' operates, in conjunction with the injector upon tube F' , to prevent any current of air (as when the lantern is suddenly lowered) passing so rapidly by the injector as to create a sufficient vacuum in the region thereof to cause the reversal of the current in F' . Thus the injector and ejector are made to operate together to sustain the current in the proper direction under all circumstances, and

this independently of the peculiar arrangement of reflector within the casing, and I propose to employ the combined ejector and injector in lanterns of other construction. The injector cap or flange G is mounted and sustained above F' , leaving openings, as at $i' i'$, through which fresh air is turned into tube F' . These openings i' might be formed by piercing the material of F' . They, together with the openings $i i$, constitute enlarged inlets, ample for the passage of any desired volume of air much greater than that which is admitted to the exposed separate tubes of previous forms of tubular lanterns, and the injector and ejector of the peculiar construction shown are capable of controlling the direction and inflow of all this air, in consequence of which I am enabled to employ a much larger burner, producing a much larger flame than in the former constructions, wherein burners of small size can only be employed with satisfactory results.

The bail or handle H is applied in sleeves h , which project through F' and E , locking these two parts together. The handle may be removed at any time.

The door-frame I carries a simple glass pane, K , which closes the front of the reflector. The frame I is hinged to the casing, as at k , upon one portion of the loop f , which forms a convenient hinge-axis. The wire of loop f may extend entirely around the casing, if desired. A spring-catch, l , serves to lock the door in closed position. The door is mainly intended to be opened when desired to clean the reflector or to remove it, and not for purposes of lighting the burner. To detach the reflector the screw d is removed, the casing tipped back, and the door opened, when the reflector may be easily unseated and withdrawn.

L is a convenient spring, bent so as to permit any board or other object—such as the dash-board of a wagon or carriage—to enter between the casing and spring, the lantern being then sustained upon the object, whatever it may be. The inner ends of the spring enter the casing from the top, and the spring may be detached by simply drawing it out of place at any time.

All the parts of the lantern are simple and easy to construct, easy to assemble, and require no expensive machinery for their manufacture. The glass pane, if broken, can be readily replaced by any one.

When constructed in accordance with the above explanations, the lantern or lamp is found in practice to admirably answer all the purposes or objects of the invention previously set forth.

Having now fully described my invention, what I claim as new, and desire to secure by Letters Patent, is—

1. In combination with the casing having an air-injector at top, the closed reflector fitting over the burner-cone and located within said casing, forming therewith a space or

chamber for the passage of the injected air-currents to the under side of the burner-cone, the oil-fount, the burner-cone, and the smoke-tube, the parts being arranged substantially as explained, so that the air-currents inside and outside the reflector will be balanced or counterbalanced, substantially as shown and described.

2. The combination of the hinged casing, the oil-fount, the burner, the burner-cone, the closed reflector, the smoke-tube connected with the reflector, and the ejector applied upon the mouth of said tube, the parts being arranged as explained, so as to compel the air to pass from the chamber between the reflector and casing, and up through the cone and reflector, substantially as and for the purposes set forth.

3. The combination of a hinged casing, an air-injector applied thereon, the oil-fount, burner-cone, closed reflector, smoke-tube connected therewith, and an ejector applied upon the smoke-tube, the parts being arranged as explained, so as to balance and direct the air-currents, substantially as shown and described.

4. The oil-fount, the closed reflector, the

casing, the smoke-tube connected with the reflector and having an ejector applied thereon, the upwardly-extending air-tube having the injector applied upon its top and having the perforations in its side walls, and the interior flaps, arranged and combined substantially as shown and described.

5. The combination, with the hinged casing having the hinged door applied thereon, of the wire loop secured upon the wall of said casing and extending above the bottom thereof, forming an abutment for the door to shut against, substantially as shown and described.

6. The combination, with the oil-fount, of the inclined rim applied thereon, and the casing hinged to said rim and arranged to enter the same, substantially as and for the purposes set forth.

In testimony that I claim the foregoing I have hereunto set my hand in the presence of two witnesses.

LEWIS F. BETTS.
